UNITED STATES PATENT OFFICE.

HARRY E. KHOURY, OF NEW BEDFORD, MASSACHUSETTS.

WARP STOP MOTION FOR LOOMS.

Application filed December 11, 1922. Serial No. 606,194.

To all whom it may concern:

Be it known that I, HARRY E. KHOURY, a citizen of Syria, residing at New Bedford, in the county of Bristol and State of Massachusetts, have invented new and useful Improvements in Warp Stop Motions for Looms, of which the following is a specification.

This invention relates to warp stop motions for looms, and more particularly to the type wherein the harness heddles perform the additional function of detector wires to stop the loom whenever one of the warp threads break.

An object of the invention is to provide a stop motion which is simple in construction and hence readily applicable to a loom, and which, at the same time, is positive and accurate in operation.

Stop motions of this general type are broadly old, and it is a well known expedient to employ the heddles for automatically stopping the loom. The present invention is an improvement upon existing stop motions of this type. In accomplishing the objects of the invention there is provided upon each heddle a loop through which passes a rocking bar mounted in the heddle frame and adapted to be rocked as the frame

is vertically reciprocated in the loom operation. The bar is rocked as the heddle frame moves and preferably extends adjacent means adapted to effect this movement. In the illustrated embodiment of the invention, the rocking means comprises an arm movable by mechanism operated from the cam shaft of the loom, and in association with such arm is provided knock-off mechanism and means for actuating such mechanism.

The knock-off mechanism comprises a finger which is movable relatively to the remainder of the mechanism and is maintained out of engagement with the actuating means as long as the warp threads are unbroken. Whenever one of the threads breaks, the rocking bar is maintained against rocking movement, which serves to prevent oscillation of the yoke arm and results in the subsequent operation of the knock-off mechanism by the aforementioned actuating means.

In the accompanying drawings there is

illustrated one form of a device embodying the invention, and in these drawings:

Fig. 1 is an end elevation of the loom 55 with the lay removed in order to more clearly disclose the stop motion structure.

Fig. 2 is a top plan view.

Fig. 3 is a view on the line 3—3 of Fig. 1 looking in the direction of the arrow. 60

Fig. 4 is a partial end elevation showing a different relative position of the parts of the stop motion during its operation.

Fig. 5 is a view similar to Fig. 4, showing the relative position of the parts when 65 one of the warp threads breaks and the knock-off mechanism is actuated.

Fig. 6 is a vertical section taken on the line 6—6 of Fig. 3.

Fig. 7 is a vertical section through the 70 heddle frames showing the position of a heddle when one of the threads breaks.

Fig. 8 is a detail view showing the spring tension means for the rocking bars, and

Fig. 9 is a detail of the stop for limiting 75 the rocking movement of one of the bars.

Referring to the drawings for a more detailed description, like numbers representing corresponding parts throughout the several views, 10 indicates a portion of the loom 80 frame in which is mounted the crank shaft 11 driven by a belt 12 adapted to be shifted between fast and loose pulleys 13 (Figs. 1 and 2) on the crank shaft, and beneath the crank shaft is mounted a cam shaft 14 85 driven from the crank shaft by means of gears 15, 16. The frame carries the usual shipper lever 17 extending through a slotted guide plate 18 (Fig. 2) and normally positioned in a notch 18' at one end thereof. 90 The lever actuates a belt shifting lever 19 pivoted at 20 upon a bracket 21 secured to the frame. Heddle frames 22, in the present instance two in number, and which are of rectangular construction, as more clearly 95 shown in Fig. 3, are vertically movable by means of lifter straps 23, the latter extending upwardly from the frames and secured to cams 24 upon a shaft 25 which receives a rocking movement from driving mechanism (not shown). Springs 26 (Fig. 3) secured to the lower ends of the heddle frames and suitably anchored to a fixed member on the loom frame, serve to tension the frames 100

when they are lifted by the cams, and to draw the frames downwardly when the shaft 25 is rocked. As much of the illustrated mechanism which has been described 5 is ordinary in loom construction, no further description is thought to be necessary since it does not constitute part of the present invention. The heddles, shown more clearly in Figs. 6 and 7, comprise central eyes 28 10 through which the warp threads pass, top loop portions 29 and bottom loops 30. Substantially circular shafts 31 pass through the bottom and top loops, and the loops 29 also have extending therethrough a non- 15 circular bar 32 mounted in each heddle frame and vertically movable therewith. The bar 32 in each frame is adapted to have imparted thereto a rocking movement; one circular end extends through the frame and 20 has anchored thereto a coil spring 33 maintained in a housing 34 (Figs. 8 and 9). The spring is fixedly secured to the frame by passing its end 35 through an opening in the frame whereby rocking movement of the 25 bar tends to tension the spring, which serves to return the bar to normal position. The housing 34 is maintained upon the end of the bar by means of a set screw 36 and is cut away at one side to provide a slot or 30 opening 37 therein, into which projects a stop finger 38 (Fig. 9) serving to limit the rocking movement of the bearing and housing under the actuation of the rocking means, the reverse actuation of the spring 35 33.

The opposite end of each bar 32 in its frame carries an extension 39 of non-circular cross section extending adjacent means adapted to rock the bars as the heddle 40 frames move. In the present instance this means is shown in the form of yokes, each yoke having the two depending arms 40, 41 which are pivotally connected by a stud 42. The arm 41 of each yoke is pivotally connected by means of a stud 45 to a reciprocable bar 46 having an extension portion 47 (Fig. 1) adjustably connected thereto by means of a bolt 48 passing through aligned slots in the two sections of the bar; 50 and the arm 40 of each yoke has passing through its terminal portion a rod 43 to which it is secured, as by set screw 44 (Fig. 3). One end 46' of bar 46 (Fig. 2) extends laterally and has passing therethrough the 55 rod 43 by which it is supported and guided in its reciprocable movements. The yokes are thus supported jointly by the rod 43 and the bar 46, the arm 41 of each yoke being normally oscillated by the bar 46 which has 60 a longitudinal reciprocable movement from operating mechanism later to be described. The extensions 39 of the rocking bars 32, together with the bars, move vertically with the heddle frames, the extensions travelling 65 in their respective yokes. The arms of each

yoke are provided, respectively, with shoulders 40', 41', and as the bar extensions 39 approach the shoulders, the oscillating movement of the arms 41, tends to rock the bars in a counter-clockwise direction, each 70 extension being normally maintained in the slanted position shown in Figs. 4 and 5. As the bar approaches the shoulder 40' it engages the latter, and the subsequent approach of the arm 41 toward the arm 40 75 completes the rocking of the bar in opposition to its tensioning spring 33 (Fig. 8).

The arms 41 and bar 46 to which they are connected are actuated in the following manner:

To the extension 47 of the bar 46 is pivotally connected (Figs. 4 and 5) one arm of a bell crank lever 50 fulcrumed at 51 upon a plate 52 supported upon an arm 53 extending through a frame bracket 54. The opposite end of the bell crank lever 50 is pivotally connected to a curved link 55 which slidably passes through a block 56 pivotally mounted upon a stud in the forked end 57 of a continuously moving power operated lever 58. A spring 65 surrounds the link 55 and serves to move the bell crank lever 50 when compressed by downward movement of the lever 58. Upon upward movement of the lever 58 it engages a stop nut 66 thereon, which reversal moves the bell crank lever 50 and thereby reciprocates the bar 46 in the opposite direction. It will thus be noted that the connection between the lever 58 and the rod 46 is a yielding one by reason of the 130 interposition of the spring 65 and link 55. The lever 58 is fulcrumed upon a stud 59 upon the bracket plate and is actuated by a pitman 60 connected to the lever 59, and at its lower end to a lever 61 pivotally mounted 105 upon a frame bracket 62 at one side of the cam shaft 14. The lever 61 carries a cam block 63 engaging double cam 64 upon the cam shaft by means of which the levers 61 and 58 are actuated. The provision of a 110 double-cam 64 insures two upward movements of the lever 61 and pitman 60 for each rotation of the drive shaft 14. In other words, there is a downward or stopping movement of the lever 58 for each pick. 115

When no warp threads are broken, the bar 46 and the arms 41 are actuated, the movement of the arms serving to rock the bars 32 when the extensions 39 thereof approach the lower portion of the yoke. When one of the warp threads breaks, the heddle, which is normally supported by the warp threads, drops to the position shown in Fig. 7, and the narrow portion 29' at the upper end of the heddle loop 29 interlocks with the bar 32, and, as the latter moves downwardly, prevents the bar from rocking. As a consequence the bar extension 39 passes below the shoulders 40', 41' of the yoke arms in its original slanted position, as indicated in 130

Fig. 5 locked against rocking movement. When either bar is locked the extension 39 of the bar prevents the yoke arm 41 from moving toward arm 40 as indicated in Fig. 5, and, through mechanism now to be described, causes operation of the loom knock-off mechanism.

The extension 47 of the bar 46 has pivotally connected thereto a finger 69 by means of a stud 70. Adjacent its upper end the finger is pivotally connected at 71 to an arm 72 of a lever 73 pivoted at its upper end 74 to the bracket plate 52. The lower end of the lever 73 is pivotally secured by means 15 of a loop 75 to the end of rod 43 which is longitudinally movable in a bearing bracket 76 (Fig. 2) and has an end hook portion 43' adapted to engage the shipper lever and throw the latter out of recess 18' in guide 20 plate 18 (Fig. 2). During reciprocation of the bar 46 and its extension 47 the finger 69 is moved about its pivot 71 without moving the lever 73 or the rod 43. The finger 69, together with the lever 73 and rod 43, are a 25 portion of the knock-off mechanism of the loom which is power operated from cam 64 through pitman 60 and lever 58, and the finger 69, during the ordinary operation of the loom, when no warp threads are broken, 30 is moved relatively to the remainder of the mechanism in the manner just described. This pivotal movement maintains the upper end 69' of the finger 69 out of engagement with a latch or lug 78 fixedly secured to the lever 58, and as the lug is moved downwardly during the operation of lever 58, it clears the tip of the finger, and moves across the inclined face 69'' of the finger, as indicated 35 in Fig. 1, the clearance between the latch 40 78 and the tip of the finger 69 being due to the movement of the finger top to the left from the position indicated in Fig. 4. In other words, the knock-off mechanism is power operated, and the movements of the 45 fingers 69 and lug 78 of the mechanism are so timed that upon downward movement of the lug the finger is given a counter-clockwise movement through bar 46 and bell crank 50 about its pivot 71 from the position 50 shown in Fig. 4 to that shown in Fig. 1. The finger is in the position shown in Fig. 4 when the lug 78 is about to make its downward stroke, during the course of which movement the lever 58 moves the arms 41 of 55 the yokes and the bar 46 to the right, as viewed in Fig. 4. In order to maintain this clearance between the finger 69 and latch 78 the extension 47 of the bar 46 may be adjusted relatively to the bar, this adjustment serving to increase or decrease the 60 amplitude of movement of the finger, depending upon the direction the extension is moved relative to the bar. Should one of the threads break, this results in the dropping 65 of its heddle and the engagement of

the narrow passage 29' of the heddle loop 29 with the bar 32 which engagement continues as the heddle frame descends. The bar 32 is thereby locked against rocking movement as its extension 39 descends to the lower portion of the yoke. When the extension 39 passes below the shoulders 40', 41' of the yoke without turning, as shown in Fig. 5, the arm 41 is held against movement to the right, as viewed in Fig. 5. As the lug 78 70 upon the lever 58 descends, it engages the tip of fingers 69 (Fig. 5) thereby throwing the lever 73 to the right and actuating rod 43 to which the lever is connected. The hooked end 43' of the rod engages the shipper lever 17, and throws the same out of the recess 18', thereby permitting the spring 17' (Fig. 1) to actuate the lever and to shift the belt through the belt shifting lever 19.

Spring 43'' upon rod 43 is placed under 80 tension as the rod is moved to the right, due to the fact that it abuts the bracket 76 and serves to return the rod and lever 74 to normal position after the shipper lever has been thrown, the stop collar 44' limiting the 85 movement of the rod 43 under the actuation of the spring.

It will be understood that the cam 64 is constantly actuating the lever 58 and pitman 60 and effects two upward or stopping 90 movements of the pitman 60 for each rotation of the drive shaft 14. In other words, there is an operating or stopping movement downward of that portion of the lever 58 bearing the latch or lug 78 for each pick, 100 which will result in the stopping of the loom should a warp thread break before another pick occurs subsequent to the breakage.

It will be understood that numerous details of the illustrated and described structure may be modified materially without departing from the scope of the invention, the latter being more definitely defined in the following claims.

I claim:

1. In a warp stop motion for looms, the combination with the heddle-frame and heddles, of a loop connected to each heddle, a rocking bar mounted in the frame and passing through the loops, means on the loops 115 for preventing rocking of the bar when any one of the threads breaks, a yoke comprising a pair of pivotally connected arms, said bar passing between the yoke arms and being vertically movable with said frame, 120 means for swinging one of said arms, a knock-off mechanism, and means connected to one of said movable yoke arms for operating said knock-off mechanism, said arm being engageable by said bar, when the latter 125 is held against rocking movement, to cause actuation of said knock-off operating mechanism.

2. In a warp stop motion for looms, the combination with the heddle frame and hed-

dles, of a loop connected to each heddle, a rocking bar mounted in the frame and movable therewith, said bar passing through the loops, means on the loops for preventing 5 rocking of the bar when any one of the threads breaks, a yoke formed of a pair of pivotally connected arms between which said bar passes, yielding means for moving one of said arms, said bar being adapted to engage 10 said arm and to prevent pivotal movement of the arm when rocking movement of the bar is stopped, a knock-off mechanism, and means for operating said mechanism, said means being rendered operative 15 only when movement of said yoke arm is prevented by said bar.

3. In a warp stop motion for looms, the combination with the heddle frame and heddles, of a loop on each heddle, a rocking bar 20 mounted in the frame and passing through the loops, means for preventing rocking of the bar when any one of the threads breaks, a movable member on the loom adjacent which said bar extends, means for continuously 25 moving said member, said bar being adapted to hold the member against movement when one of the threads breaks and rocking of the bar is prevented, a knock-off mechanism, and means for actuating said knock-off mechanism, said means being operative 30 only when said member is held against movement by said bar.

4. In a warp stop motion for looms, the combination with the heddle frame and heddles, of a rocking bar associated with the heddles and mounted in the heddle frame, means for holding the bar against rocking movement when one of the warp threads breaks, a continuously moving arm mounted 35 on said loom, means on said bar adapted to engage the arm when the bar is held against rocking movement, and to prevent movement of the arm, yielding means for actuating said arm, a knock-off mechanism, and means for operating said mechanism, said means comprising a finger pivotally 40 movable through connections with said arm, a knock-off bar operatively connected to said finger, and a member on said arm moving 45 means adapted to engage and to actuate said finger to throw said bar only when pivotal movement of said finger is stopped.

5. In a warp stop motion for looms, the combination with the heddle frame and heddles, of a bar associated with the heddles and movably mounted in the heddle frame, the heddles being formed to permit the bar to pass therethrough and being adapted to lock the bar against movement when one of the warp threads breaks, means adapted to move the bar in one direction as the heddle frame moves, power operated mechanism for continuously moving said bar moving means, the bar being adapted to restrain said means 60 against movement when one of the warp 65

threads breaks, knock-off mechanism, power operated means for actuating said knock-off mechanism, and connections between said bar moving means and the knock-off mechanism whereby the latter is operative only 70 when the bar moving means is restrained against movement by the locking of the bar.

6. In a warp stop motion for looms, the combination with the heddle frame and heddles, of a rockable bar associated with the heddles and mounted in the heddle frame, means on the heddles for holding the bar against rocking movement when one of the warp threads breaks, a movable arm mounted 75 on said loom and adapted to rock said bar, yielding means for moving said arm, said bar being adapted to lock said arm against movement when one of the warp threads breaks, knock-off mechanism, and means for actuating said knock-off mechanism, said means being operatively only when said arm is held against movement and comprising a pivoted finger, a continuously operating lever, and a latch on said lever for engaging the finger, the finger being maintained out of engagement with the latch by the movement of said arm.

7. In a warp stop motion for looms, the combination with the heddle frame and heddles, of a rockable bar associated with the heddles and mounted in the heddle frame, means on the heddles adapted to engage and to hold the bar against rocking movement when one of the warp threads breaks, a movable member engaging said bar and rocking 100 the same, yielding means for moving said member, said bar being adapted to prevent movement of said member when the bar is held against rocking movement, knock-off mechanism comprising a finger pivotally 105 movable by the means which move said member, and power operated means for engaging said finger to actuate said mechanism, said finger being normally maintained out of contact with said means by the movement of said member.

8. In a warp stop motion for looms, the combination with the heddle frame and heddles, of a rockable bar associated with the heddles and vertically movable with the heddle frame, means on the heddles adapted to engage and to hold the bar against rocking movement when one of the warp threads breaks, a yoke having a pair of arms one of which has an oscillatory movement, said bar extending between the arms and said movable arm serving to rock the bar, yielding means for actuating said yoke arm, said bar serving to prevent movement of the arm when the bar is locked against rocking, knock-off mechanism and means for actuating said mechanism, said means being rendered operative only when the yoke arm is held against movement by said bar.

9. In a warp stop motion for looms, the

- combination with the heddle frame and heddles, of a rockable bar associated with the heddles and mounted in the heddle frame, means on the heddles adapted to engage and hold the bar against rocking movement when one of the warp threads breaks, yielding means for maintaining the bar against rocking movement, a yoke mounted upon the loom and having a pair of depending arms one of which is pivotally movable relative to the other arm, said bar extending between said arms, means for oscillating said movable arm, said arm serving to rock the bar, the latter being movable longitudinally of said yoke, and said bar serving to prevent movement of the arm when the bar is held against rocking movement by one of the heddles, yielding means for oscillating said arm, knock-off mechanism comprising a finger pivotally movable relative to the remainder of the mechanism through connections with said arm, and means for actuating said finger, said means engaging the finger only when the yoke arm is locked against oscillatory movement.

10. In a warp stop motion for looms, the combination with the heddle frame and heddles, of a rockable bar associated with the heddles and vertically movable with the heddle frame, means on the heddles adapted to engage and to hold the bar against rocking movement when one of the warp threads breaks, spring means for normally maintaining the bar against rocking movement, a yoke having a pair of depending arms and mounted upon a stationary portion of the loom, said bar extending between the arms of the yoke and vertically movable relative to the yoke, means for moving one of the arms of said yoke, said movable arm serving to rock said bar and the bar being adapted to hold the arm against movement when the bar is locked against rocking movement, yielding means for moving said yoke arm comprising a reciprocating rod and a lever for actuating said rod, knock-off mechanism comprising a finger pivotally movable by said reciprocating rod relative to the remainder of the mechanism, and knock-off actuating mechanism adapted to engage the finger, said actuating mechanism engaging the finger only when movement of the yoke arm is stopped.

11. In a warp stop motion for looms, the combination with a heddle frame, a series of heddles adapted to be supported in said frame by the warp threads, of a rockable bar movably mounted in the heddle frame, the heddles being formed to permit the bar to extend therethrough and being adapted to engage and lock the bar against movement when one of the warp threads breaks, means on the loom separate from the bar adapted to rock the bar as the heddle frame moves, and power actuated means to stop the loom, said stop means being maintained inoperative as long as the bar is free to move under the influence of said actuating means.

12. In a warp stop motion for looms, the combination with a heddle frame, heddles supported therein by the warp threads, of a bar movably mounted in the heddle frame, the heddles being formed to permit the bar to extend therethrough and being adapted to lock the bar against movement when one of the warp threads breaks, means on the loom frame and separate from the lay adapted to move said bar in one direction as the heddle frame moves, and power actuated means actuatable independently of said bar to stop the loom, said stop means being maintained inoperative through said bar moving means as long as the bar is unlocked and free to be moved thereby.

13. In a warp stop motion for looms, the combination with a heddle frame, heddles supported therein by the warp threads, of a rockable bar movably mounted in the heddle frame, the heddles being formed to permit the bar to extend therethrough and being adapted to lock the bar against movement when one of the warp threads breaks, means on the loom adapted to rock said bar in one direction as the heddle frame moves, spring means for rocking the bar in the opposite direction, and power actuated means to stop the loom, said stop means being maintained inoperative through said bar moving means as long as the bar is unlocked and free to be moved thereby.

14. In a warp stop motion for looms, the combination with a heddle frame, heddles supported therein by the warp threads, of a rockable bar movably mounted in the heddle frame, the heddles being formed with loops through which said bar extends and being adapted to lock the bar against movement when one of the warp threads breaks, means separate from the bar on the loom adapted to be engaged by and to rock said bar in one direction as the heddle frame moves, and power actuated means to stop the loom, said stop means separate from the lay being maintained inoperative through said bar moving means as long as the bar is unlocked and free to be moved thereby.

15. In a warp stop motion for looms, the combination with a heddle frame, heddles supported therein by the warp threads, of a bar movably mounted in the heddle frame, the heddles being formed with loops through which said bar extends and being adapted to lock the bar against movement when one of the warp threads breaks, means on the loom adapted to be engaged by and to move said bar in one direction as the heddle frame moves, spring means for moving the bar in the opposite direction, and power actuated means separate from the lay

to stop the loom, said stop means being maintained inoperative through said bar moving means as long as the bar is unlocked and free to be moved thereby.

5 16. In a warp stop motion for looms, the combination with a heddle frame and heddles supported therein by the warp threads, of a bar movably mounted in the heddle frame, the heddles being formed to permit 10 the bar to extend therethrough and being adapted to engage and lock said bar against movement when one of the warp threads breaks, power operated moving means separate from the bar on the loom adapted to 15 move the bar as the heddle frame moves, and power operated means to stop the loom, said stop means being maintained inoperative only as long as the bar is free to be moved by said bar moving means.

20 17. In a warp stop motion for looms, the combination with a heddle frame and heddles supported therein by the warp threads, of a bar movably mounted in the heddle frame, the heddles being formed to permit 25 the bar to extend therethrough and being adapted to engage and lock said bar against movement when one of the warp threads breaks, power operated moving means on the loom separate from the bar adapted to 30 move the bar as the heddle frame moves, said bar when locked restraining said moving means against movement, and power operated means to stop the loom, said stop means being maintained inoperative only 35 as long as the bar is free to be moved by said bar moving means.

18. In a warp stop motion for looms, the combination with a heddle frame and heddles supported therein by warp threads, of 40 a bar movably mounted in the heddle frame, the heddles being formed to permit said bar to extend therethrough and being adapted to engage and lock said bar against movement when one of the warp threads breaks, 45 power operated moving means on the loom adapted to engage and to move the bar as the heddle frame moves, and power operated means actuatable independently of said bar to stop the loom, said stop means being 50 maintained inoperative through said bar actuating means only as long as the bar is free to be moved by said actuating means.

55 19. In a warp stop motion for looms, the combination with a heddle frame and heddles supported therein by warp threads, of a bar movably mounted in the heddle frame, the heddles being formed with loops through 60 which said bar extends and being adapted to engage and lock said bar against movement when one of the warp threads breaks, power operated moving means on the loom frame adapted to move said bar as the heddles frame moves, said means being restrained by said bar when the same is locked 65 by one of said heddles, and power operated

means to stop the loom, said means being maintained inoperative through said bar moving means until the latter is restrained against movement by the locking of the bar.

70 20. In a warp stop motion for looms, the combination with a heddle frame and heddles supported therein by warp threads, of a bar movably mounted in the heddle frame, the heddles being formed with loops through which said bar extends and being adapted to engage and lock said bar against movement when one of the warp threads breaks, power operated moving means on the loom frame adapted to engage and to move 75 said bar as the heddle frame moves, said means being restrainable by said bar when the same is locked by one of said heddles, and power operated means to stop the loom, said means being maintained inoperative until the bar moving means is restrained 80 against movement by the locking of the bar.

85 21. In a warp stop motion for looms, the combination with a heddle frame and heddles supported therein by warp threads, of a bar movably mounted in the heddle frame, the heddles being formed with loops through 90 which said bar extends and being adapted to engage and lock said bar against movement when one of the warp threads breaks, power operated moving means on the loom frame adapted to move said bar as the heddle frame moves, said means being restrained by said bar when the same is locked by one of said heddles, and power operated means to stop the loom, said loom stop means comprising a source of power, connections between said source of power to a loom shipper lever, said connections being maintained inoperative by connections with said 95 bar moving means until the latter is restrained against movement by the locking of the bar.

100 22. In a warp stop motion for looms, the combination with the heddle frame and heddles, of a bar movably mounted in the frame, each heddle having a loop through which said bar passes, means on the heddles for preventing moving of the bar; when any one of the threads breaks, a movable arm on the loom, separate from the bar, means separate from the lay for moving said arm, said bar being movable by said arm in one direction, a knock-off mechanism, connections between said knock-off mechanism and said arm, the arm and its connections 105 normally maintaining said knock-off mechanism inoperative, but permitting operation of the knock-off mechanism when the bar is held against movement.

110 23. In a warp stop motion for looms, the combination with a heddle frame and heddles, of a bar movably mounted in the frame, each heddle having a loop through which said bar passes, means on the heddles 115 for preventing movement of the bar when 120 normally maintaining said knock-off mechanism inoperative, but permitting operation of the knock-off mechanism when the bar is held against movement.

125 130

- any one of the threads breaks, a movable arm on the loom, means separate from the lay for moving said arm, said bar being movable by said arm in one direction, spring 5 means for moving the bar in the opposite direction, a knock-off mechanism, connections between said knock-off mechanism and said arm, said knock-off mechanism being normally maintained inoperative through 10 said connections but permitting operating when the bar is held against movement.
24. In a warp stop motion for looms, the combination with a heddle frame and heddles, of a rocking bar mounted in the 15 frame and movable therewith, each heddle being provided with a loop through which said bar passes, means on the heddles for preventing rocking of the bar when any one of the threads breaks, a movable arm 20 on the loom frame adjacent which the bar extends, power operated yielding means for moving said arm, said arm when moved in one direction rocking the bar, said bar being adapted to prevent movement of the 25 arm when rocking movement of the bar is stopped, a knock-off mechanism, power means for operating said mechanism, said means being rendered operative only when movement of said arm is prevented by the 30 locking of the bar.
25. In a warp stop motion for looms, the combination with the heddle frame and heddles, of a rocking bar mounted in the frame and movable therewith, each heddle 35 being provided with a loop through which said bar passes, means on the heddles for preventing rocking of the bar when any one of the threads breaks, a movable arm on the loom frame adjacent which the bar extends, power operated yielding means for 40 moving said arm, said arm when moved in one direction rocking the bar, spring means for rocking the bar in the opposite direction, said bar being adapted to prevent movement of the arm when rocking movement of the bar is stopped, a knock-off mechanism, power operated means for 45 operating said mechanism, said means being rendered operative only when movement of said arm is prevented by the bar.
26. In a warp stop motion for looms, the combination with a heddle frame and heddles, of a rocking bar mounted in the frame and movable therewith, each heddle 55 being provided with a loop through which said bar passes, means on the heddles for preventing rocking of the bar when any one of the threads breaks, a movable arm on the loom frame adjacent which the bar extends, power operated yielding means for 60 moving said arm, said arm when moved in one direction rocking the bar, spring means for rocking the bar in the opposite direction, said bar being adapted to engage said arm and to prevent pivotal movement of the 65 arm when rocking movement of the bar is stopped, a knock-off mechanism, power means for operating said mechanism, said means being rendered operative only when movement of said arm is prevented by the bar.
27. In a warp stop motion for looms, the combination with the heddle frame and heddles, of a loop on each heddle, a bar movably mounted in the frame and passing through the loops, means on the heddles for preventing movement of the bar when any one of the threads breaks, an arm on the loom, means on said bar extending adjacent said arm, power operated means separate from the lay for moving the arm, said bar being adapted to hold the arm against movement when any one of the threads breaks and the movement of the bar is prevented, a knock-off mechanism and power operated means for actuating said knock-off mechanism, said means being operative only when the arm is held against movement by said bar. 75
28. In a warp stop motion for looms, the combination with the warp threads, of detector wires supported thereby, a movable bar extending through the detector wires and adapted to be locked thereby when one of the warp threads breaks, a continuously moving arm on the loom operatively associated with said bar and adapted to move the same, means on the bar adapted to engage the arm when the bar is held against movement and thereby to prevent movement of the arm, yielding means for actuating the arm, a knock-off mechanism, power actuated means for operating said mechanism, said means comprising a movable finger, connections between said arm and the finger through which the finger is moved, a knock-off bar connected to said finger, and a continuously moving member adapted to engage and to actuate said finger to throw said bar only when movement of the finger through said connections is stopped. 80
29. In a warp stop motion for looms, the combination with a heddle frame, of a series of heddles adapted to be supported in said frame by the warp threads, a bar rockably mounted in the heddle frame, the heddles being formed to permit the bar to extend therethrough and being adapted to engage and lock the bar against rocking movement when one of the warp threads breaks, means on the loom separate from the bar adapted to move the bar as the heddle frame moves, and power actuated means to stop the loom, said stop means being maintained inoperative as long as the bar is free to move under the influence of said moving means. 85
30. In a warp stop motion for looms, the combination with a heddle frame, of a series of heddles adapted to be supported in said frame by the warp threads, a bar rockably 90

mounted in the heddle frame, the heddles being formed to permit the bar to extend therethrough and being adapted to engage and lock the bar against rocking movement 5 when one of the warp threads breaks, means on the loom separate from the bar adapted to move the bar as the heddle frame moves, and power actuated means actuatable independently of the movement of the heddle 10 frame to stop the loom, said stop means being maintained inoperative as long as the bar is free to move under the influence of said moving means.

31. In a warp stop motion for looms, the 15 combination with a heddle frame, a series of heddles adapted to be supported in said frame by the warp threads, of a rockable bar movably mounted in the heddle frame, the heddles being formed to permit the bar 20 to extend therethrough and being adapted to engage and lock the bar against movement when one of the warp threads breaks, means on the loom separate from the bar adapted to rock the bar as the heddle frame 25 moves, and power actuated means to stop the loom, said stop means being maintained inoperative as long as the bar is free to move under the influence of said actuating means, and including a continuously moving 30 member, and means driven from the loom drive shaft for imparting a movement to said member before every pick, any one of said movements being adapted to effect stoppage of the loom when said bar is locked.

32. In a warp stop motion for looms, the 35 combination with a heddle frame, heddles supported therein by the warp threads, of a rockable bar movably mounted in the heddle frame, the heddles being formed with

loops through which said bar extends and 40 being adapted to lock the bar against movement when one of the warp threads breaks, means separate from the bar on the loom adapted to be engaged by and to rock said bar in one direction as the heddle frame moves, and power actuated means to stop the loom, said stop means being maintained inoperative through said bar moving means as long as the bar is unlocked and free to be moved thereby and including a continuously moving member, and a cam driven from the loom drive shaft for imparting movement to said member before every pick, any one of said movements being adapted to 50 effect stoppage of the loom when said bar is locked.

33. In a warp stop motion for looms, the combination with a heddle frame and heddles supported therein by the warp threads, of a bar movably mounted in the heddle frame, the heddles being formed to permit the bar to extend therethrough and being adapted to engage and lock said bar against movement when one of the warp threads breaks, means on the loom adapted to move 55 the bar as the heddle frame moves, and power operated means to stop the loom, said stop means being maintained inoperative only as long as the bar is free to be moved by said bar moving means, and including a continuously moving member, and a cam adapted to impart thereto a movement before every pick, any one of said movements being adapted to effect stoppage of the loom when said bar is locked.

In testimony whereof I have hereunto set my hand.

HARRY E. KHOURY.
